ATTORNEY

UNITED STATES PATENT OFFICE

ANTON SCHIERER, OF HINSDALE, ILLINOIS

STOVE INCLOSURE

Application filed May 3, 1928. Serial No. 274,947.

This invention relates to new and useful improvements in stove inclosures, and more particularly to a device of this character which is especially adapted for use in connection with cooking stoves. One of the objects of my invention is the provision of an inclosure which will inclose the upper part of a cook stove with the front portion open, so that access may be easily obtained to the grates and ovens.

Another object of my invention is the provision of a device of the above character which is provided with a supporting frame of special structure for the purpose of supporting the inclosure in its proper position relative to the stove, whereby the inclosure will be extremely useful in conveying the undesirable odors arising from cooking, off to any desired place.

20 A further object of the device is the provision of a structure which can be readily connected to an outside draft and so disposed relative the cooking grates as to create a draft over the cooking grates and convey 25 the steam, smoke and cooking odors to the outside and prevent them from escaping into the room in which the stove is located.

With the above and other objects in view, the invention consists in the novel features of construction, the combination and arrangement of parts hereinafter more fully set forth, pointed out in the claim and shown in the accompanying drawings, in which

30 Figure 1 is a front elevation of my device illustrating its application,

Figure 2 is a vertical sectional view on the line 2—2 of Figure 1, and

Figure 3 is a horizontal sectional view on the line 3—3 of Figure 1.

40 For the purpose of properly illustrating my invention, it will be noted that I have shown a cook stove 1 in the body of the inclosure 2. The upper or dome part 3 of the inclosure has its front and end walls curved 45 on an arc, as shown at 4, and terminate at their upper part into an outlet 5. The back of the part 3 is perpendicular or practically vertical, as at 6, and also terminates into the outlet 5 which is connected with a draft conduit 7.

The body part 2 comprises a back wall 8 and ends walls 9, the upper edge of which is formed with inturned flanges 10, upon which rest the inturned flanges on the lower edge of the part 3 and back wall 6, said flanges being connected and held against movement by means of bolts, rivets or similar fastening means.

55 In order to properly support the body and dome, a frame 11 is provided, which comprises the legs 12, end pieces 13 and longitudinal piece 14, which connect the legs and are suitably braced by means of the diagonal brace members 15. The upper ends of the legs are formed with inturned flanges to which inturned flanges on the body are bolted, so as to securely retain the body in place on the frame.

60 Suspended from the front edge of the part 3 is a swinging guard plate 16, which when in use is suspended from the part 3, as shown in full lines in Figure 1, and, when not in use, is moved to rest in an inclined position against the part 3, as shown in dotted lines in Figure 1. This plate 16 is used particularly when there is any cooking done from which considerable odor or smoke is arising, so as to keep all but a minimum amount from escaping into the room in which the stove is located.

65 It will be apparent from the foregoing that I have provided an extremely useful device which when applied to cooking stoves will convey the smoke and odors from the cooking to the outside and wherein suitable means are provided for regulating the draft in a damper plate 17, manually operable by means of a chain 18, connected thereto.

70 While I have shown and described the preferred embodiment of my invention, it will be apparent that various changes and alterations may be carried out without departing from the spirit of the invention or the scope of the appended claim.

75 I claim as my invention:
In an inclosure of the class described, a supporting frame having horizontal flanges thereon, a body portion open at one side and having internal flanges at its upper and lower edges with the flanges on the lower

edges resting on and secured to the flanges on the frame, a dome part having arcuate front and end walls and a vertical back wall all terminating into a draft opening, inturned flanges on the lower edge of the dome part resting and secured to the flanges at the upper edge of the body, and a guard plate pivotally suspended from the lower edge of the dome part and adapted to be extended over a portion of the open side of the body.

10 In witness whereof, I have hereunto set my hand this 11th day of April, A. D. 1928.

ANTON SCHIERER.
